FREDERICK W. KLEIN, Inventor

By Attorney *Ed. Kelly.*

UNITED STATES PATENT OFFICE.

FREDRICK WM. KLEIN, OF READING, PENNSYLVANIA, ASSIGNOR TO THE READING BRAID COMPANY, OF SAME PLACE.

DESIGN FOR BRAID-CORD.

SPECIFICATION forming part of Design No. 25,817, dated July 21, 1896.

Application filed May 14, 1896. Serial No. 591,582. Term of patent 7 years.

To all whom it may concern:

Be it known that I, FREDRICK WM. KLEIN, a citizen of the United States, residing at Reading, in the county of Berks and State of Pennsylvania, have invented a new and original Design for Braid-Cord; and I do hereby declare the following to be a full, clear, and exact description of the same.

The accompanying drawing shows a piece 10 of braid-cord fully illustrating my design.

The leading feature of my design is the smooth-edged cord effect *a* on one edge of the braid, formed of a series of colored threads, each set of threads forming a solid color, as 15 *b* and *c*, and arranged diagonally, as shown. The colors can be arranged alternate or otherwise, as desired, and any number of colors can be used; but each color remains separate from the others. The threads are wound in 20 distinct strands, do not intersect, and form a smooth edge, which, in connection with the

diagonally-arranged colors, produces a pleasing effect.

The body of the braid *d* consists of a number of threads braided through each other, as shown, but forms no essential feature of my design, which consists alone of the smooth cord-edge effect.

While the drawing shows the cord effect on one edge only, it is evident that it can be 30 made as well with the same effect on both edges if desired.

What I claim is—

The design for braid-cord, substantially as herein shown and described. 35

In testimony whereof I affix my signature in presence of two witnesses.

FREDRICK WM. KLEIN.
